INVENTOR
James McCormick

UNITED STATES PATENT OFFICE.

JAMES McCORMICK, OF POTSDAM, NEW YORK.

CARRIAGE-SPRING.

SPECIFICATION forming part of Letters Patent No. 307,724, dated November 4, 1884.

Application filed August 15, 1884. (No model.)

To all whom it may concern:

Be it known that I, JAMES McCORMICK, of the town of Potsdam, county of St. Lawrence, and State of New York, have invented certain new and useful Improvements in the Springs of Carriages and Light Wagons; and I do hereby declare that the following is a full, clear, and exact description of the same, reference being had to the accompanying drawings, in which like letters of reference represent like parts, and in which—

Figure 1 is a perspective view of a carriage-body and axle-frame having my improvement, and Fig. 2 is a plan view of the same with the body removed.

In ordinary carriages and light wagons wherein the body is raised from the axle-frame by the interposition of the common elliptic springs there is a constant tendency to rack and strain the latter by reason of the imparted momentum continuing to act upon the carriage-body after the wheels and axle-frame have reached a partial or entire state of rest. Especially is this so in those sudden stoppages occasioned by the wheels in rapid revolution striking obstructions, which tend not only to stop the progress of the vehicle, but to set in violent vertical vibration the springs themselves. In this way breakages both of the springs and of their fastenings to the axle-frame and the carriage-body are constantly occurring. Various means have been heretofore devised having in purpose the overcoming of this tendency to breakage. In none, however, with which I am acquainted, has the important function of the "edge-bend" elliptic spring been retained, while at the same time holding the body firmly to the same with a constant elastic pressure.

To this end my improvement consists in supporting the ordinary carriage or light-wagon box or body upon the vehicle or axle-frame by means of a front and rear elliptic edge-bend spring, set each with its upper half or portion inclined toward the other, to form, with the bottom of the body, a firm brace, and combining therewith a central longitudinal spring, secured at each end to the axle-frame, and in the middle by an adjustable strap or other device to each side of the body. The body is thus elastically braced against unrestrained

movement in any direction. Its momentum cannot rack the elliptic springs at their ears or joints, and thus cause the same to work loose and become rickety, for they are braced against each other; and no bounce, however sudden or severe, can throw the body upward to the derangement or detriment of the edge-bend springs, for the central longitudinal spring holds the body firmly, but yieldingly, upon the said springs, and these to their seat upon the axle-frame; nor can the elliptic springs strike each other at their centers on the rebound, the edge bend permitting the top half of each spring to go freely past the bottom half thereof.

A is the ordinary box or body of a carriage or light road-wagon.

B B are the front and rear axles, respectively.

C C are the perches or reaches coupling the front and rear axles, and thus forming the vehicle or axle frame.

D D are the cross-bars, secured to the reaches near to and parallel with the axles. To these cross-bars is attached centrally, by any suitable means, the single longitudinal spring E. This spring is reversed with reference to the box or body, its normal action being to counteract any upward movements of the said body. To this end it is secured to the box or body by an adjustable device, such as straps F F, one of which passes up from each side of the spring to the bottom of the body at or near its side margins.

To give the spring liberty to expand and contract under the saltatory movements of the edge-bend springs that support the carriage-body when the vehicle strikes an obstruction, as well as to meet the necessities of the varying adjustments of the same with reference to the carriage-body and the axle-frame, respectively, provision must be made for its loose or free connection with the fixed parts of the axle-frame. Any free attachment may be employed; but I preferably use the ordinary shackle, which allows perfect freedom of movement, is wholly secure, and not liable to break.

G G are the edge-bend elliptic springs upon which the box or body is supported. Their upper halves are secured to the sills or bol-

sters of the body-bottom, and their lower halves are fastened to the axle-frame by any suitable means. These springs, which I term "edge-bend" or "circle-bend," have each the 5 upper half on the center on one side of a vertical plane passing through the ears, while the other or bottom half at the center is on the opposite side of the said vertical plane. By this construction the two halves can freely pass 10 each other when the springs collapse without their centers coming into contact. I set the front spring with its top half inclined backward, while the rear spring has its top half inclined forward, thus forming a permanent 15 brace when united to the body, preventing all swaying and back-and-forth movement of the body independent of the movement of the running-frame.

The construction being as described, it is 20 apparent that a light, firm, elastic attachment of the body to the axle-frame is secured. The central longitudinal spring, by its adjustable attachment to the outer margins of the body-bottom, binds the same firmly, but yieldingly, 25 to the bracing edge-bend elliptic springs, preventing thus both lateral strain as well as longitudinal rocking of the elliptic springs. In other words, by my construction I secure a 30 twofold function for the edge-bend springs by adding the central longitudinal spring, whose normal action does not impair but adds to the function of the said springs, causing them to act with the body as braces each to the other, and at the same time to fulfill their normal function as edge-bend springs. 35

It is manifest that departures may be made in the arrangement and construction of the parts herein described and shown. These, however, coming within the scope of my improvements, I do not in any manner abandon, 40 being within the spirit of my invention.

I have preferably shown and described a single central longitudinal spring to hold with

elastic pressure the carriage-body to the running or axle frame, wherein the said body is 45 supported upon the edge-bend springs described; but it is manifest that my invention embraces not only a central longitudinal spring, by which to secure, in the combination recited, the advantages I have set forth, 50 but that any equivalent form of spring or springs—such as side springs or end springs—by the intervention of which the edge-bend elliptic springs are made to act as elastic braces to support and hold the carriage-body 55 to the axle-frame, may be employed instead.

Having thus described my invention, what I claim as new, and desire to secure by Letters Patent of the United States, is—

1. The combination, with the carriage body 60 or box and the axle-frame, of the edge-bend front and rear elliptic springs inclined toward each other to form a brace, and the central longitudinal spring secured to the axle-frame, and having means for attachment to the body, 65 whereby the body is normally held with yielding pressure upon the said edge-bend elliptic springs as set forth.

2. The combination, with the carriage body 70 or box and the axle-frame, of the edge-bend front and rear elliptic springs inclined toward each other to form a brace, and the central longitudinal spring secured to the axle-frame, and having adjustable means for attachment 75 to the body, whereby the same is normally held with yielding pressure upon the said edge-bend elliptic springs, and the force of the said pressure is adapted to be regulated and controlled to suit the same to the varying weights brought to bear upon the springs, as 80 set forth.

JAMES McCORMICK.
